A. J. WALTON

VALVE SPRING LIFTER

Filed March 31, 1925

INVENTOR

Arthur J. Walton.

BY

BY
Albert E. Dietrich
ATTORNEY

UNITED STATES PATENT OFFICE.

ARTHUR J. WALTON, OF TAKOMA PARK, DISTRICT OF COLUMBIA.

VALVE-SPRING LIFTER.

Application filed March 31, 1925. Serial No. 19,673.

To all whom it may concern:

Be it known that I, ARTHUR J. WALTON, a citizen of the United States, residing at Takoma Park, in the District of Columbia, ⁵ have invented certain new and useful Improvements in Valve-Spring Lifters, of which the following is a specification.

My invention is an improved tool used for the purpose of lifting the valve springs ¹⁰ of an internal combustion engine to enable the valves to be ground without the necessity of removing the springs.

Primarily the invention has for its object to provide a very simple and inexpensive ¹⁵ tool that can be used to lift all the valve springs of an engine at one and the same time and hold them so without the employment of screws, hooks, special cams or other more or less costly devices.

In carrying out my invention, which has been especially designed for use on Ford engines having a single valve spring housing or chamber, I provide a flat rigid plate ²⁰ with a set of slots to pass over the valve stems and under the valve spring cups or washers and also provide the same with a pair of longer slots to fit over the valve cover screws, on which screws the tool is fulcrumed as a part of a lever, the remainder ²⁵ of which is constituted by a handle having a forked end to straddle the edge of the plate and adapted, when the plate has been rocked, to raise the springs, to have its outer end caught under the hook rail and thereby hold the plate in the lifting position while the valves are being ground.

The invention further resides in those ⁴⁰ novel details of construction, combination and arrangement of parts, all of which will be first fully described, then be specifically pointed out in the appended claims, reference being had to the accompanying drawing, in which:—

Figure 1 is a perspective view of a cylinder block showing my invention in use.

Figure 2 is a detailed cross section of the same showing the position of the parts in full lines with the springs lifted and in dotted lines before the lifting action is ⁵⁰ accomplished.

Figure 3 is a perspective view of the valve spring lifter plate viewed from the underside.

Figure 4 is a perspective view of the handle part. ⁵⁵

In the drawing, in which like numerals indicate like parts in all the figures, 1 is a flat narrow plate of comparatively rigid material, such as steel, and this plate around one edge is provided with a series of slots 2, one for each valve spring, suitably positioned so that the plate may be inserted under all of the valve springs at one and the same time. The plate is also provided with two additional slots 4 to fit over the spring cover plate screws of the engine which serve as fulcrums for the plate. Associated with each slot 4 I preferably provide bearing lugs or heels 5 suitably formed or secured on the plate 1. The forward end of the plate 1, where it is to be passed beneath the valve spring cups or washers, may be and preferably is, bevelled as at 3 to facilitate the entrance of the plate to position. ⁶⁰

7 is the handle which is forked at 8 to straddle over the back edge 6 of the plate 1, and by means of which the plate is rocked on the bearings 5 until the springs have been compressed, at which time the lever ⁶⁵ 7 is swung laterally as on a pivot and passed under the edge of the hood holding down strip or frame part of the automobile as diagrammatically indicated in Figure 2 of the drawing, thus holding the plate in the ⁷⁰ position to hold the valve springs lifted and leaving the valve stems free from the action of the springs as long as the plate and lever remain in this position. ⁷⁵

It will be seen that by my construction a ⁸⁰ simple and inexpensive tool has been provided for the purpose which can be readily carried in the tool box of the car, which can be manufactured at a nominal cost and which will effectively serve its intended purpose. ⁸⁵

From the foregoing description, taken in connection with the accompanying drawing, it is thought the complete construction and advantages of my invention will be clear to those skilled in the art to which it relates. ⁹⁰

What I claim is:

1. In valve spring lifters, a plate having a series of valve stem receiving slots along one edge, and a pair of valve-cover-screw receiving slots along the same edge, and an operating handle having provision to en- ¹⁰⁰ ¹⁰⁵

gage the opposite edge of said plate for the purpose of rocking the plate on said screws substantially as shown and described.

2. In valve spring lifters, a plate having 5 a series of valve stem receiving slots along one edge, and a pair of valve-cover-screw receiving slots along the same edge, an operating handle having provision to engage the opposite edge of said plate for the purpose 10 of rocking the plate on said screws, said handle being movable laterally parallel to the plane of the plate as on a pivot for the purposes described.

3. In valve spring lifters, a plate having 15 a series of valve stem receiving slots along

one edge, and a pair of valve-cover-screw receiving slots along the same edge, an operating handle having provision to engage the opposite edge of said plate for the purpose of rocking the plate on said screws, 20 and bearing lugs on said plate associated with said valve-cover-screw receiving slots for the purposes specified.

4. A valve spring lifter tool composed of two parts, a flat plate and a handle forked 25 to receive the plate, said flat plate having a series of valve-stem-receiving slots and a set of valve-cover-screw-receiving slots along one edge for the purposes specified.

ARTHUR J. WALTON.
